(57) **CLAIM**

The ornamental design for a table, as shown and described.

DESCRIPTION

FIG. 1 is a perspective view of a table.

FIG. 2 is a front elevation view thereof.

FIG. 3 is a right side elevation view thereof.

FIG. 4 is a rear elevation view thereof.

FIG. 5 is a left side elevation view thereof.

FIG. 6 is a top plan view thereof.

FIG. 7 is a bottom plan view thereof.

FIG. 8 is a cross sectional view thereof taken along line 8—8 in FIG. 2.

FIG. 9 is a cross sectional view thereof taken along line 9—9 in FIG. 2.

FIG. 10 is a cross sectional view thereof taken along line 10—10 in FIG. 2.

FIG. 11 is a right side elevation view thereof where the tabletop is raised; and,

FIG. 12 is a left side elevation view thereof where the tabletop is raised.

The portion of the article shown in broken lines is for the purpose of showing interior structure only and forms no part of the claimed design.
